UNITED STATES PATENT OFFICE.

WILLIAM MITCHELL, OF MILWAUKEE, WISCONSIN, ASSIGNOR TO MITCHELL MANUFACTURING COMPANY, OF MILWAUKEE, WISCONSIN, A CORPORATION OF WISCONSIN.

REVOLVING SWING.

Application filed August 24, 1925. Serial No. 52,084.

This invention relates to improvements in revolving swings.

It is one of the objects of the present invention to provide a swing apparatus suited for playgrounds and yards.

A further object of the invention is to provide a revolving swing apparatus arranged to accommodate a plurality of persons and easily operated.

10 A further object of the invention is to provide a swing apparatus which will afford exercise and amusement to those operating and using it and which is so constructed that a child cannot be injured thereby.

15 A further object of the invention is to provide a swing apparatus in which the seat may swing in any direction with respect to the central support.

20 A further object of the invention is to provide a swing apparatus provided with a novel suspension means for the seat permitting free movement of the seat, the seat and braces having a parallelogram movement so that the seat will at all times be 25 parallel to the ground.

A further object of the invention is to provide a revolving swing having an efficient anti-friction bearing.

25 A further object of the invention is to provide a revolving swing which is of very simple construction, is strong and durable, is neat and attractive in appearance, and is well adapted for the purpose described.

With the above and other objects in view 35 the invention consists of the improved revolving swing, and its parts and combinations as set forth in the claims, and all equivalents thereof.

In the accompanying drawing in which 40 the same reference characters indicate the same parts in all of the views:

Fig. 1 is a front view of the improved revolving swing;

Fig. 2 is an enlarged detail sectional view 45 of the seat and suspension means therefor;

Fig. 3 is an enlarged detail sectional view of the central support and the upper bearing for the swing frame;

Fig. 4 is an enlarged fragmentary detail 50 view showing the connection of a seat supporting member with the swing frame; and

Fig. 5 is an enlarged detail view of the lower bearing for the swing frame.

Referring now more particularly to the

drawing it will appear that the improved 55 revolving swing is indicated by the numeral 8. An elongated tubular post 9 provided with a suitable base is embedded in the ground and the upper portion of the post 9 receives a cap member 10 fitted therewith and formed with an outwardly flanged upper edge 12 to rest on the upper edge of the post 9.

A bearing member 13 is revolvably mounted on the top of the post 9 and cap 10. An 65 annular inner recess is formed between the member 13 and the cap 10 and in said recess a plurality of ball bearings 14 are disposed to facilitate the turning of the bearing member, an oil jacket 15 surrounding said ball 70 bearings.

An aperture 16 is provided in the top of the bearing member and a flag pole 17, threaded into the cap 10 extends upwardly through said aperture. 75

A swing frame, designated generally by the numeral 18, comprises a plurality of radially extending braces 19 carried by a collar 20, to be later explained, and radially and downwardly extending stays 21 secured to each of the braces at their outer ends and to the bearing member 13 at their inner ends. Also, the outer ends of the braces 19 are secured and connected by horizontal members 22. 85

As was mentioned, the inner ends of the braces 19 are secured to a collar 20 which is shown in detail in Fig. 5. Said collar revolvably surrounds a medial portion of the post 9 and is of cupped formation to hold 90 roller bearings 23 which ease the turning of the collar on the post. The collar 20 is connected to the bearing member 13 by means of four straps 24 having bent end portions 25 and bolted to the flanged edge portions of the members 13 and 20 respectively. It will, therefore, be evident that the swing frame is suspended by the post 9 and turns thereon, by means of the bearing member 13, the collar 20, and the straps 24 connecting 100 the same.

The swing seat is preferably of octagonal shape and comprises flat elongated seat members 26 connected together by flat castings 27, the castings having extensions 28 105 extending rearwardly and upwardly therefrom to form braces for the rear rails 29. The midportions of the castings 27 are

formed with sockets 30 to receive the ball end portions 31 of seat suspension rods 32 forming a universal joint connection for the seat. The ball portions 31 are removably held by the enlarged lower end portions of the suspension rods 32, as shown in Fig. 2.

The upper end portions of the suspension rods 32 are also connected to the end portions of the radial frame members 19 in a manner so as to permit the free movement of said rods in all directions. As shown in Fig. 4, hook shaped members 33 are secured to the end portions of the members 19 and said hook shaped members loosely engage depending looped members 34, the looped members being free to swing forwardly and rearwardly. The upper end portions of the suspension rods 32 are hook shaped and engaged by the looped members 34 in a manner to permit lateral swinging.

In operation the swing revolves around the central post and also the seat can be caused to swing inwardly and outwardly with respect to its circular line of travel.

From the foregoing description it will be seen that the improved revolving swing is of very simple and novel construction and is well adapted for the purposes set forth.

What I claim as my invention is:

1. In a revolving swing, a stationary support, a rotative frame mounted thereon, an annular swing seat surrounding the support, and rigid suspension members depending from the frame and engaging the swing seat, said suspension members having universal joint connections with the frame and with the swing seat.

2. In a revolving swing, a stationary support, a rotative frame mounted thereon, an annular swing seat surrounding the support and formed with sockets, and normally vertical suspension rods between the seat and the frame, the lower ends of said rods being formed with heads to swivelingly engage said sockets.

3. A revolving swing, comprising a central, stationary, tubular support, a cap member fitted into and covering the upper end of the support, a rotative member covering said support, anti-friction means interposed between said cap and said rotative member,

a collar rotatably mounted on the medial portion of said support, strap members rigidly connecting said collar and said rotative member, arms extending radially from said collar, braces extending from the outer ends of said arms to said rotative member, an angularly shaped annular seat surrounding the support, said seat being formed of a plurality of sections, plate members connecting said sections, each plate being provided with a socket and suspension rods for said seat, said rods having enlarged lower end portions engaging said sockets and universal joint connections with the end portions of said radial arms.

4. A revolving swing, comprising a central support, a rotative member mounted on said support, arms extending horizontally and radially from said rotative member, a vertical rod pivotally suspended from the end portion of each arm, and an annular seat suspended by said rods and swivelingly connected to the lower portions thereof.

5. A revolving swing, comprising a central, stationary support, a cap member fitted into and covering the upper end of the support, a rotative member covering said support, anti-friction means interposed between said cap and said rotative member, a collar rotatably mounted on the medial portion of said support, a rigid connection between said collar and said rotative member, arms extending radially from said collar, braces extending from the outer ends of said arms to said rotative member, an annular seat surrounding the support, sockets formed in said seat, and suspension rods for said seat, said rods having enlarged lower end portions engaging said sockets, and also being swivelingly connected at their upper ends to said arms.

6. A revolving swing, comprising a stationary support, a rotative, horizontally extending frame mounted thereon, an annular swing seat surrounding the support, and suspension rods between the seat and frame and having universal joint connections therewith, there being a parallelogram relation between the frame, the rods, and the seat.

In testimony whereof, I affix my signature.

WILLIAM MITCHELL.
